CLAIM

The ornamental design for a x-ray film viewer, substantially as shown.

DESCRIPTION

FIG. 1 is a front and side perspective view of an x-ray film viewer embodying my new design;
 FIG. 2 is a view of the side of the viewer opposite that shown in FIG. 1;
 FIG. 3 is a front view of the viewer;
 FIG. 4 is a top plan view of the viewer; and
 FIG. 5 is rear view of the viewer.
